UNITED STATES PATENT OFFICE.

CONRAD BACHMANN, OF ERIE, PENNSYLVANIA.

CUT-OFF FOR GAS-LINES.

SPECIFICATION forming part of Letters Patent No. 761,190, dated May 31, 1904.

Application filed September 21, 1903. Serial No. 174,062. (No model.)

To all whom it may concern:

Be it known that I, CONRAD BACHMANN, a citizen of the United States, residing at Erie, in the county of Erie and State of Pennsylvania, 5 have invented new and useful Improvements in Cut-Offs for Gas-Lines, of which the following is a specification.

This invention relates to safety cut-offs for gas-lines; and it consists in certain improvements in the construction thereof, as will be hereinafter fully described, and pointed out in the claims.

The object of the invention is to provide a cut-off for gas-lines which will remain open 15 during a normal pressure of gas, but will cut off the gas discharge when this pressure fails, so that when the gas is again turned on it will prevent its passage.

The invention is illustrated in the accompanying drawings, as follows:

Figure 1 shows a central vertical section of the device; Fig. 2, an elevation of the valve-operating tube; Fig. 3, an elevation of the valve.

25 A marks the valve-chamber. This has the inlet a . The outlet-tube a^2 extends up into the chamber. A flange a^3 extends around the chamber opposite the upper end of the outlet a^2 , and a flange a^4 extends outwardly from the top of the tube a^2 , forming a partial closure of the chamber at that point. Below the flanges a^3 and a^4 a receptacle A' is provided for a liquid B , preferably mercury, which forms a liquid seal for the valve. Extending 30 downwardly from the top A^2 of the chamber is a guide-ring a^5 . The valve D operates in this guide-ring. At the top of the guide-ring the under surface a^6 of the top A^2 is finished, forming a seat for the upper surface d of the 35 valve D . A vent a^7 extends from this surface. This vent is controlled by a needle-valve C . I prefer to provide the valve with a flange d' , which will steady it in the liquid seal.

Extending from the chamber opposite the 45 tube a^2 is a connection E . This is connected with a $\mathbf{T}$ F , and extending from the $\mathbf{T}$ is a pipe G , with a gland g . Extending through this gland and through the $\mathbf{T}$ F , connection E , and tube a^2 is a tube H . This tube is closed 50 at the bottom by a cap h' . It has slotted open-

ings h , which connect the tube with the $\mathbf{T}$ F , and a flange h^2 , which prevents its withdrawal from the tube a^2 . This tube H may be pushed up into the chamber A , so as to move the valve D to its upper seat. After the valve is seated by the gas-pressure the tube H may be withdrawn from the position shown in Fig. 1. 55

The operation of the device is as follows: With the needle-valve C in an open position the valve D is pushed so as to bring the surfaces d and a^6 into contact. It is held to this contact by the gas-pressure. After it is fully seated the needle-valve C may be closed. The tube H , by which the valve D is pushed to its seat, is drawn down to the position shown in 60 Fig. 1. Gas passing through the chamber passes through the tube H and through the $\mathbf{T}$ for any desired distribution. On a fall of gas-pressure the valve D drops through gravity, the lower end of the valve passing into 65 the liquid B , thus forming a complete seal as against the passage of gas through the chamber A . When gas is again turned on into the main, the valve D remains closed, and the valve C being closed no escape of gas is permitted. The device may be again opened for the passage of gas by pushing the tube H inwardly against the valve D , the operation being as just hereinbefore described. 70

What I claim as new is—

1. In a safety cut-off for gas-lines the combination of a valve-chamber having a gas-passage therethrough; a valve in said chamber arranged to be held in an open position by gas under pressure and to close the gas-passage upon a failure of pressure, and then to remain closed with a renewal of gas-pressure; and means for opening said valve. 85

2. In a safety cut-off for gas-lines the combination of a valve-chamber having a gas-passage therethrough; a valve in said chamber arranged to be held in an open position by gas under pressure and to close the gas-passage upon a failure of pressure, and then to remain closed with a renewal of gas-pressure; 90 a liquid seal for said valve; and means for opening said valve.

3. In a safety cut-off for gas-lines the combination of a valve-chamber having a gas-passage therethrough and a vent therefrom, the 95

valve arranged to be seated by the gas-pressure and to close said vent, said valve being arranged to close the gas-passage upon a failure of gas-pressure, and then to remain closed 5 with a renewal of gas-pressure; and means for opening said valve.

4. In a safety cut-off for gas-lines the combination of a valve-chamber having a gas-passage therethrough and a vent therefrom, the 10 valve arranged to be seated by the gas-pressure and to close said vent, said valve being arranged to close the gas-passage upon a failure of gas-pressure, and then to remain closed with a renewal of gas-pressure; means for 15 opening said valve; and a manually-operated valve for controlling said vent after the main valve has been seated to close said vent.

5. In a safety cut-off for gas-lines the combination of a valve-chamber having an outlet- 20 tube extending into the chamber; a valve in the form of a cap extending from said outlet-tube; a liquid seal arranged around said tube in a position to be engaged by said valve; a 25 seat for said valve in its open or upper position, said seat being of such surface that the valve is held in an open position by gas-pressure; and means for moving said valve to said seat.

6. In a safety cut-off for gas-lines the combination of a valve-chamber having a receptacle A' for the liquid seal; a guide-ring a⁵; an 30 outlet-tube a² extending up into the chamber; a vent a⁷ extending from the upper part of the chamber within the ring a⁵; the valve D normally arranged within the ring a⁵ and to be 35 held in its upper position by gas-pressure, the valve D being cap-shaped and adapted to close with the liquid seal over the outlet-tube, and said liquid seal.

40 7. In a safety cut-off for gas-lines the combination of a valve-chamber having the flange a³; the outlet-tube a² extending up into the chamber with a second flange a⁴ opposite the flange a³, said flanges and walls of the chamber forming a liquid-receptacle A'; a liquid 45

seal in said receptacle; and a cap-shaped valve arranged to extend from the outlet into the liquid seal.

8. In a safety cut-off for gas-lines the combination of a valve-chamber having the flange a³; the outlet-tube a² extending up into the chamber with a second flange a⁴ opposite the flange a³, said flanges and walls of the chamber forming a liquid-receptacle A'; a liquid seal in said receptacle; and a cap-shaped valve arranged to extend from the outlet into the liquid seal, said valve being arranged to be held in an open position by gas-pressure; and means for opening the valve.

9. In a safety cut-off for gas-lines the combination of the valve-chamber; a valve D arranged in said chamber adapted to be held in an open position by the gas-pressure and to close the gas-passage upon failure of gas-pressure; the tube H forming part of the passage 65 for the gas, said tube having slits h for the passage of gas to or from the tube, said tube H being arranged to slide into the chamber A for opening the valve D.

10. In a safety cut-off for gas-lines the combination of the chamber A having the outlet-tube a² extending up into the chamber, the flanges a³ and a⁴ inclosing the receptacle A', a guide-ring a⁵ extending from the top A² of the chamber, the top A² of the chamber having the vent a⁷ and surface a⁶ on its under side; the vent-valve C controlling the vent a⁷; the main valve D arranged in the guide-ring a⁵ having a surface d to act on the surface a⁶, the valve having the flange d'; a liquid B in 80 the receptacle A'; the tube H in the outlet-tube a² said tube H having the slot h for the purpose described.

In testimony whereof I have hereunto set my hand in the presence of two subscribing 85 witnesses.

CONRAD BACHMANN.
